FILLING-FEELER MECHANISM.

1,249,280.

Specification of Letters Patent. Patented Dec. 4, 1917.

Application filed April 3, 1916. Serial No. 23,592.

To all whom it may concern:

Be it known that I, JONAS NORTHRUP, a citizen of the United States, residing at Hopedale, in the county of Worcester and State of Massachusetts, have invented certain new and useful Improvements in Filling-Feeler Mechanisms; and I do hereby declare the following to be a full, clear, and exact description of the invention, such as will enable others skilled in the art to which it appertains to make and use the same.

The present invention relates to an improvement in filling feeler mechanisms for looms.

15 The object of the invention is to produce a filling feeler mechanism of simple construction capable of determining critical or predetermined exhaustion of filling efficaciously, so that the filling may be exhausted more 20 uniformly on the filling carriers irrespective of variations in their sizes and irrespective of whether they are obliquely positioned in the shuttle. With this object in view the invention consists of the improved and simplified filling feeler mechanism hereinafter described and particularly pointed out in the claims.

In the accompanying drawings illustrating the preferred form of the invention, 30 Figure 1 is a plan of a portion of a loom showing the application of the improved filling feeler mechanism thereto; Fig. 2 is a front elevation of the parts shown in Fig. 1; Fig. 3 is a side elevation of the same 35 looking from the right; and Fig. 4 is a section taken on the line 4-4 of Fig. 1.

The loom to which the improved filling feeler mechanism is applied may be of any usual or preferred construction, and may be 40 either a plain loom or a weft replenishing loom. If applied to a plain loom the feeler mechanism operates to stop the loom upon critical exhaustion (or exhaustion to a predetermined extent) of the filling in the shuttle; 45 and if applied to a weft replenishing loom the feeler mechanism operates to bring about the insertion in the shuttle of a fresh supply of filling upon critical exhaustion.

The portion of the loom shown in the 50 drawings comprises a breast beam 8, a weft hammer 9 pivoted on a stud 10 and oscillated by a cam actuated lever in timed relation with the movements of the lay 12 supported on a lay sword 13 for movements 55 toward and from the breast beam in the usual

manner, and a shuttle 14 having the usual slot 15 cut in its front wall and containing a filling carrier 16. The rock or change shaft 17 journaled in brackets secured to the front side of the breast beam may be connected at the end of the loom opposite the filling feeler mechanism with the weft replenishing mechanism, or it may be connected at the filling feeler end of the loom with the shipper devices by which the loom is stopped. The construction, organization, and mode of operation of these and other parts of the loom coöperating therewith are familiar to those skilled in the art.

The improved filling feeler mechanism 70 comprises a filling feeling member or filling feeler which consists of a filling engaging member 20 and a feeler lever 21. The filling engaging member is yieldingly mounted for reciprocal movements toward and from 75 the filling carrier on the feeler lever 21 which is pivoted on a pin 22 rising from a feeler lever support 23 provided with a slot 24, through which passes a bolt 25 by which the feeler support 23 is adjustably secured 80 to a plate 26 secured by a bolt and slot connection to a bracket 27, in turn secured by another bolt and slot connection to a second bracket 28 fastened to the breast beam. This construction is such that the filling feeler 85 may be adjusted vertically, transversely and obliquely with relation to the filling carrier. The filling engaging member 20 is slidingly received in guides 30 and 31 rising from the feeler lever. A compression spring 32 encircling a shank 33 formed on the forward end of the filling engaging member is interposed between a shoulder 29 at the junction of the shank and the head of the filling engaging member and the guide 30, and yieldingly presses the filling engaging member toward the filling carrier so that it may be engaged by the filling thereon. The rearward movement of the filling engaging member 90, that is, the movement toward the filling carrier, is limited by a stop pin 34 which projects downwardly from the shank 33 and comes into engagement with the forward side of a rib 35 formed on the rearward end of the feeler lever 21. The rear or filling engaging end of the filling engaging member 20 is serrated or provided with filling engaging teeth 37. When the filling on the filling carrier 16 strikes the filling feeler on the forward beat of the lay when the shuttle 110

is boxed at the filling feeler end of the lay, this being termed the filling feeling beat of the lay, these serrations or teeth 37 coöperate with the filling to prevent movement of the filling feeler longitudinally of the filling carrier. It will be observed that the filling engaging end of the filling engaging member 20 lies on a line drawn through the axis of the pivot pin 22 and disposed at right angles to the filling carrier when the parts of the filling feeler mechanism are in normal position, as shown in Fig. 1. Consequently, when the filling carrier on the filling feeling beat of the lay strikes the filling engaging teeth, the pressure exerted by the filling on the filling engaging member 20 moves it straight forward on this line. The pressure of the filling carrier on the filling engaging member 20, therefore, does not impart or tend to impart an oscillatory movement to the filling feeler, that is, it does not tend to cause the filling engaging member and the feeler lever 21 to turn on their pivot pin 22. Other and independent means are provided for effecting this turning movement.

The filling feeler mechanism is connected with either the loom stopping means or the weft replenishing mechanism through the rock or change shaft 17 by loom controlling devices comprising an arm 39 rigidly secured to the rock shaft 17, a lever 40 pivoted on a pin 41 projecting laterally from the arm 39, and a latch lever 42 arranged to swing horizontally on a pivot pin 43 carried by the rearward end of the lever 40. A torsion spring 44 encircling the rock shaft 17, one end of the spring taking against the loom frame and the other end of the spring taking against the lower end of the arm 39, tends to maintain the arm 39 in inward position toward the breast beam and the levers 40 and 42 in the position shown in Figs. 1 and 3. The filling feeler mechanism is articulated with the loom controlling devices by means of a link 46, one end of which is loosely received in a hole in the forward end of the feeler lever 21, the other end of the link being loosely received in a hole in the head of an adjustment bolt 47 threaded in the forward end of the latch lever 42. By disengaging the link 46 from the head of the bolt 47 and turning the bolt inwardly or outwardly, the interrelation of the latch lever and the feeler lever may be adjusted. A lightly tensioned compression spring 48 interposed between the latch lever and the inner end of a screw 49 threaded into the rear end of the lever 40, tends to swing the latch lever and the feeler lever to the right or clockwise about their pivots and thereby bring a shoulder 50 formed on the rearward end of the latch lever into the path of motion of a bunter 51 formed on the weft hammer. By means of the screw 49 the tension of the spring 48 may be adjusted. The posi-

tion of the shoulder 50 may be adjusted relatively to the bunter 51 of the weft hammer by means of an adjustment screw 54 threaded into the upper end of an extension 55 projecting upwardly from the arm 39. The inner end of the adjustment screw 54 bears against a boss 56 on the front of the breast beam. A lock nut 57 secures the screw in adjusted position. The limit of swing of the latch lever is determined by a stop lug 38, formed on the forward end of the latch lever, coming into engagement with the adjacent side of the lever 40.

As is usual, the weft hammer beats forward and returns once while the lay beats forward and returns twice; consequently, these parts are so timed in their movements that, when the weft hammer is beginning its forward beat, the shuttle being boxed at the filling feeler side of the loom, the lay on its filling feeling beat has already brought the filling carrier into contact with the filling engaging end of the filling engaging member 20. While the parts of the loom controlling devices and the filling feeler mechanism are in their normal positions as shown in Fig. 1, that is, before the weft hammer and the lay have moved forward, the pivotal movement of the levers 42 and 21 is prevented by the engagement of the weft hammer with a projection 59 laterally extending from the extreme rear end of the latch lever. When the forward movement of the weft hammer has disengaged it from the projection 59, the tendency of the spring 48 to force the shoulder 50 into the path of motion of the bunter 51 will be counteracted, so long as any filling remains on that part of the filling carrier opposite the filling engaging member 20, by the engagement of this filling with the filling engaging teeth. But, when the filling opposite the filling engaging member 20 has become entirely exhausted, the spring 48, acting on the filling feeler through the connections between them, causes the filling engaging teeth to travel along the unwound surface of the filling carrier toward the butt thereof. This longitudinal movement of the filling feeler along the filling carrier is arrested by the end winding of the filling. But when the filling has been unwound or exhausted to a predetermined point from the butt of the filling carrier, the feeler lever and necessarily the latch lever will have swung far enough to the right, under actuation of the spring 48, to bring the shoulder 50 into the path of motion of the bunter 51, which will then move forward the parts of the loom controlling devices to oscillate the rock shaft 17 and thereby set in operation either the weft replenishing mechanism or the means for causing loom stoppage. In this connection it will be observed that by reason of the above-described construction of the feeling feeler mechanism and its con-

nection with the loom controlling devices, the extent to which the filling on the filling carrier is to be exhausted is determined by the adjustment of the filling feeler and its supporting means longitudinally of the filling carrier. The farther from the butt of the filling carrier the filling feeler is positioned, the more filling is left on the filling carrier; and, conversely, the nearer to the butt of the filling carrier the filling feeler is positioned, the less filling is left on the filling carrier. It is thus seen that the quantity of filling to be left on the filling carrier when the loom controlling devices are to be set in operation, may be accurately determined.

When the bunter 51 on the weft hammer moves opposite the open space rearwardly of the latch shoulder on the filling feeling beat of the lay and the corresponding forward movement of the weft hammer, and there is a substantial amount of filling on the filling carrier, the coöperation between the filling and the filling engaging member 20 prevents the spring 48 from turning the latch lever 42. After the bunter 51 has passed by the shoulder 50, it engages the inner side of the rear end of the latch lever, and thereby holds it and the feeler lever in normal position when the backward beat of the lay has disengaged the filling from the filling engaging member. When on the rearward movement of the weft hammer the bunter 51 arrives opposite the open space rearwardly of the latch shoulder 50, (the shuttle at this time being at the opposite side of the loom), the spring 48 will of course turn the latch lever 42 and the feeler lever. This turning of the two levers obviously causes no change in the operation of the loom, and is but momentary, because as the weft hammer continues its rearward movement it engages the inturned end 59 on the latch lever, thereby forcing the latter and the feeler lever into their normal positions, as shown in Fig. 1. Thus it is seen that at all times during the operation of the loom, except when the bunter is opposite the open space rearwardly of the latch shoulder, the coöperation between the latch lever and the weft hammer maintains the feeler lever in normal position and incidentally prevents the weft hammer from acting, through the latch lever, on the loom controlling devices. But when the bunter is opposite the open space and a substantial amount of filling is on the filling carrier, the filling in coöperation with the filling feeler prevents the latch lever from turning. We have, then, a coöperative action between the weft hammer, the latch lever, the filling and the filling feeler, to prevent a change in the operation of the loom until critical exhaustion of filling.

It will be observed that in the present con-

struction of filling feeler mechanism the filling engaging member may have a reciprocating movement toward and from the filling carrier of indefinite length; consequently, variations in the sizes of the filling carriers will not affect the accuracy of determining the extent to which the filling on them shall be exhausted. And so, also, an obliquely positioned filling carrier in the shuttle will have no effect on the accuracy of the filling feeling operation.

The reason why this uniformity in exhausting all filling carriers is secured, irrespective of their size or position in the shuttle, will be apparent when it is considered that the presence of filling on that part of the filling carrier opposite the filling engaging teeth of the filling feeler prevents the pivotal movements of the filling feeler, and consequently of the latch lever, when the weft hammer bunter moves opposite the recess in the latch lever. Accordingly the filling must be unwound or exhausted to a predetermined point from the butt of the filling carrier before a change in the operation of the loom is effected.

Having thus described the invention, what is claimed is:—

1. A loom having, in combination, a weft hammer having a bunter, loom controlling devices including a latch lever having a shoulder, a filling feeler mechanism including a feeler lever, connections between the latch lever and the feeler lever, and means tending to force the shoulder of the latch lever into the path of motion of the bunter, the latch lever and the weft hammer having parts coöperating with each other and the filling feeler mechanism coöperating with the filling to prevent engagement of the latch lever shoulder by the bunter until the filling has been exhausted to a predetermined extent.

2. A loom having, in combination, a weft hammer, loom controlling devices including a latch lever, a filling feeler mechanism including a filling feeler having a feeler lever, connections between the latch lever and the feeler lever, and means tending to move the levers, said latch lever and weft hammer having coöoperating parts by virtue of which the movement of the levers is prevented until the filling engages the filling feeler.

3. A loom having, in combination, a weft hammer, loom controlling devices including a latch lever having provision for engagement with the weft hammer, a filling feeler mechanism including a feeler lever and a filling engaging member, connections between the latch lever and the feeler lever, and means tending to move the levers, the engagement of the filling with the filling engaging member and the engagement of the weft hammer with the latch lever preventing movement of the levers until the filling

has been exhausted to a predetermined extent.

4. A loom having, in combination, a movable member, a filling feeler mechanism, and loom controlling devices having provision for being set in operation by the movable member when the filling has been exhausted to a predetermined extent, said filling feeler mechanism, loom controlling devices and movable member all coacting to prevent the movable member from setting the loom controlling devices in operation until the filling has been exhausted to a predetermined extent.

5. A loom having, in combination, a shuttle, a filling carrier, a weft hammer having a bunter, loom controlling devices including a latch lever having a shoulder, a filling feeler mechanism including a feeler lever and a filling engaging member mounted on the feeler lever, connections between the latch lever and the feeler lever, and means tending to move the latch lever shoulder into the path of motion of the bunter and the filling engaging member toward the butt of the filling carrier, the filling and the filling engaging member coöperating on the filling feeling beat of the lay to prevent the shoulder from moving into the path of the bunter until the filling has been exhausted to a predetermined point from the butt of the filling carrier, the latch lever and the weft hammer having coöperating parts to hold the latch lever and the feeler lever in normal position until the filling has engaged the filling engaging member.

6. A loom having, in combination, a weft hammer, loom controlling devices including a latch lever, a filling feeler mechanism comprising a pivoted feeler lever and a filling engaging member yieldingly mounted on the feeler lever, connections between the latch lever and the feeler lever, and a spring tending to swing the latch lever and the feeler lever and thereby bring the latch lever into position to be engaged by the weft hammer on its forward beat, said movement of the latch lever and the feeler lever being prevented by the engagement of the filling with the filling engaging member on the filling feeling beat of the lay until the filling has been exhausted to a predetermined extent, said movement of the latch lever and the feeler lever being also prevented by the operation of the weft hammer and the latch lever until the filling has engaged the filling engaging member.

7. A loom having, in combination, a movable member, loom controlling devices adapted to be engaged by the movable member to effect a change in the operation of the loom when the filling is exhausted to a predetermined extent, means tending to move the loom controlling devices into the path of motion of the movable member, and a filling

feeler mechanism including a filling feeler, said loom controlling devices and movable member having parts coöperating to prevent the loom controlling devices from moving into the path of motion of the movable member until the filling engages the filling feeler, whereupon the coöperation of the filling and the filling feeler prevents the loom controlling devices from moving into the path of motion of the movable member until the filling is exhausted to a predetermined extent.

8. A loom having, in combination, a movable member, a latch adapted to be actuated by the movable member, a feeler, and connections between the movable member, latch and feeler operating automatically in coöperation with the filling to hold the latch from actuation by the movable member until the filling has been exhausted to a predetermined extent.

9. A loom having, in combination, a lay, a shuttle, a filling carrier, a breast beam, a support secured thereto, a feeler lever pivoted on the support, a filling engaging member slidably and yieldingly mounted on the feeler lever and adapted to engage with the filling, loom controlling means, a latch lever connected therewith, a link connecting the two levers, means tending to move the levers, and a weft hammer having parts coöperating with the latch lever to hold the levers in normal position until the filling feeling beat of the lay and to permit the turning of the levers when the filling has been exhausted to a predetermined extent.

10. A loom having, in combination, a lay, a weft hammer, a shuttle, a filling carrier, a breast beam, a support, a feeler lever pivoted thereon, a filling engaging member slidably and yieldingly mounted on the feeler lever and adapted to coöperate with the filling to determine its state of exhaustion, means tending to turn the feeler lever, and means for positively preventing the turning of the lever at all times except when the filling engages the filling engaging member, and except on the return movement of the weft hammer.

11. A loom having, in combination, a filling feeler mechanism comprising a pivoted filling feeler adapted on predetermined exhaustion of filling to move longitudinally of the filling carrier in engagement with the denuded surface thereof and with the exhausting filling, loom controlling devices including a latch lever, positive connections between the latch lever and the filling feeler, means for moving the latch lever and the filling feeler on predetermined exhaustion of filling, and a weft hammer, said latch lever and said weft hammer having parts coöperating to hold the filling feeler in normal position until it has been engaged by the filling.

12. A feeler mechanism for looms, com-

prising a feeler member pivotally mounted to swing about a fixed axis and having a part to engage the filling in the shuttle, means tending to turn said feeler member

5 about said fixed axis, and cam means for moving the feeler about its fixed axis into feeling position in opposition to said means.

13. In a feeler motion for looms, the combination of an operating member, an arm 10 having a part for engagement by said operating member to actuate said arm and effect filling replenishment, means normally acting to move said part into position for engagement by said operating member, means carried by said arm to prevent movement of said arm in response to said normally acting means during a portion of the movement of the operating member, and a feeler acting by contact with the filling in the shuttle 15 until substantial exhaustion thereof to pre-

vent movement of said arm in response to said normally acting means during the remainder of the movement of the operating member.

14. In a feeler motion for looms, the combination of an operating member, an arm having a part for engagement by said operating member to effect filling replenishment when the filling in the shuttle is substantially exhausted, a feeler connected to said arm and having a part to engage the filling in the shuttle and to be held from movement longitudinally of the shuttle until substantial exhaustion of the filling, means tending to move the feeler longitudinally of the shuttle, and means carried by said arm adapted to be engaged by the operating member on its backward movement to return the feeler to feeling position. 25 30 35

JONAS NORTHROP.
